UNITED STATES PATENT OFFICE.

EDWIN P. WELLESLEY AND CHARLES WELLESLEY, OF COLON, MICHIGAN.

WINDMILL.

SPECIFICATION forming part of Letters Patent No. 337,641, dated March 9, 1886.

Application filed July 8, 1885. Serial No. 171,008. (No model.)

To all whom it may concern:

Be it known that we, EDWIN P. WELLESLEY and CHARLES WELLESLEY, citizens of the United States of America, residing at Colon, 5 in the county of St. Joseph and State of Michigan, have invented certain new and useful Improvements in Windmills; and we do hereby declare the following to be a full, clear, and exact description of the invention, such as will 10 enable others skilled in the art to which it appertains to make and use the same, reference being had to the accompanying drawings, and to letters or figures of reference marked thereon, which form a part of this specification.

15 Our invention relates to certain new and useful improvements in horizontal wind-wheels; and it consists in the construction and combination of the parts, as will be hereinafter fully set forth, and specifically pointed out in the 20 claims.

25 In the accompanying drawings, which illustrate our invention, Figure 1 is a side view of a wind-wheel constructed in accordance with our invention. Fig. 2 is a vertical sectional view, and Fig. 3 is a horizontal sectional view taken through the line $z z$ of Fig. 2.

30 A represents a suitably-constructed supporting-frame, the upper ends of the beams of which are rigidly attached to a circular frame, A', which is provided with cross-bars a , which 35 unite at their center, so as to form a bearing, a' , through which the vertical shaft B passes.

To the under side of the circular frame A' are pivotally secured, by means of staples b , 35 the levers C, the outer end of each of which is bent upwardly, as shown in Fig. 2, so as to engage with projections on the under edge of the ring D, which fits loosely over the outer edge of the circular frame A'. The under edge 40 of the ring D is formed with projections for the reception of the upwardly-bent ends of the levers C, which levers are depressed by the weight of the ring upon their outer ends. The inner ends of the lever abut against the central portion of the frame A' when their outer 45 ends are depressed, so as to support said ring below the plane of the circular frame A'. The levers C have attached near their inner ends, which converge toward each other, cross-bars 50 C', to which are connected flexible cords d , with chains d' , by means of which they can be secured to the frame A, so as to raise the outer

ends of the lever and hold the ring D above the plane of the circular frame A', and thus throw the wind-wheel out of action, as will be 55 hereinafter fully set forth. The vertical shaft B is mounted in a horizontal beam, E, so that the collar thereon will rest upon the upper surface of the same, and the upper end of the shaft is rigidly connected to the horizontal circular 60 frame F with central cross-beams, f . The upper periphery of the circular frame F is provided on opposite sides with bearing-blocks g , and at right angles therewith with similarly-constructed bearing-blocks g' , which are of a 65 greater height. In the bearing-blocks $g g'$ are journaled horizontal shafts G, to the ends of which are attached the vanes V, said vanes being secured to said shaft on one side of their centers, as shown in Fig. 2, so that the major 70 portion of said vanes will depend from said shafts. The shafts are provided adjacent to the frame F with projecting pins H, which are parallel with the inner edges of the vanes, the aforesaid pins being adapted to engage with 75 projections formed in the outer periphery of the circular frame F, these projections being indicated by h , and said pins, when in a vertical position, project beyond the lower edge of the frame F. The vanes which are attached 80 to the opposite ends of the shafts lie in different planes, so that when one is vertical the opposite plane will be horizontal. A conical cap, I, is attached to the frame F by means of vertical bars i , and said cap projects beyond the 85 edge of the frame, so as to protect the bearings and said frame from the weather. The vertical shaft B is provided at its lower end with the gear-wheel, which meshes with a similar gear-wheel attached to a horizontal shaft, to 90 which the machinery to be driven is connected.

The operation of our improvement is as follows: The wind when coming from any point will strike against the vane, and will turn the same to a vertical position, in which position 95 it is held by the pin H, which engages with the corresponding projection, h , on the rim of the frame F. The greater portion of the vane being below the shaft will prevent the same from turning, and while said vane is in a vertical position the opposite vane will be horizontal, so as to present a straight edge and but little resistance to the wind. The wind will act continuously upon the different vanes,

and when not acting upon the same said vanes will remain inclined with respect to the frame at opposing angles. When it is desired to throw the windmill out of action, the cords *d* 5 are tightened, so as to throw the outer ends of the lever upwardly, and thus raise the ring *D*, so that it will bear against the under edge of the circular frame *F*, thus holding each of the vanes in an inclined position, so that the wind *o* will not act upon the same. The pins *H* do not come into contact with the ring *D* when the same is lowered, and the motion of the wheel is not retarded by the same trailing upon the upper edge of this ring.

5 We claim—

1. In a horizontal windmill, the combination, with a vertical shaft carrying a revolving frame having projections upon its periphery, of the vane-carrying shafts having pins arranged to engage the said projections, a vertically-moving ring constructed to engage the revolving frame and pins, and the levers pivoted upon the shaft-supporting frame and constructed to raise the ring, as described.

2. The combination, with the vertical shaft 25 *B*, and the revolving frame mounted thereon and carrying the shafts *G*, of the frame *A'*, the vertically-adjustable ring *D*, constructed to engage the revolving frame, and the levers *C*, pivoted to frame *A'* and arranged to raise the 30 ring *D* into engagement with the revolving frame, as and for the purposes set forth.

3. The combination, with the frame *A*, carrying portion *A'* and shaft *B*, and the levers *C*, pivoted to portion *A'* and provided with cords 35 *d*, of the revolving frame *F*, carrying the vane-shafts and secured to shaft *B*, and the ring *D*, arranged to engage with the revolving frame, as and for the purposes specified.

In testimony whereof we affix our signatures 40 in presence of two witnesses.

EDWIN P. WELLESLEY.
CHARLES WELLESLEY.
